UNITED STATES PATENT OFFICE

99,901

DESIGN FOR A SHOE

Harry Snayberger, Schuylkill Haven, Pa.

Application February 18, 1936, Serial No. 61,223

Term of patent 3½ years

To all whom it may concern:

Be it known that I, Harry Snayberger, a citizen of the United States of America, residing in Schuylkill Haven, county of Schuylkill, and State of Pennsylvania, have invented a new, original, and ornamental Design for a Shoe, of which the following is a specification, reference being had to the accompanying drawing, forming part thereof,

Fig. 1 is a plan view of a shoe showing my new design.

Fig. 2 is a side elevational view of a shoe as shown in Fig. 1.

Fig. 3 is the other side of the shoe as shown in Fig. 2.

The shoe has perforations on one side with high cut effect on side as shown in Fig. 2.

The other side of shoe has no perforations with special low cut effect on side as shown in Fig. 3.

I claim:

The ornamental design for a shoe substantially as shown and described.

HARRY SNAYBERGER.
